GEORGE F. KUEHN, OF SPRINGFIELD, MASSACHUSETTS, ASSIGNOR TO LEON W. ROSENTHAL, OF SPRINGFIELD, MASSACHUSETTS.

JACK.

1,420,114.

Specification of Letters Patent. Patented June 20, 1922.

Application filed January 5, 1921. Serial No. 435,246.

To all whom it may concern:

Be it known that I, GEORGE F. KUEHN, a citizen of the United States, residing at 22 Crestwood Street, Springfield, in the county 5 of Hampden, State of Massachusetts, have invented certain new and useful Improvements in Jacks; and I do hereby declare the following to be a full, clear, and exact description of the invention, such as will enable others skilled in the art to which it 10 appertains to make and use the same.

The present invention relates to jacks, and particularly to jacks of the telescopic kind having a housing with two or more spindles 15 adapted for longitudinal movements relatively to each other and to the housing for the purpose of providing a large extension with a comparatively small collapsed height.

While jacks of this general kind are 20 known, the means heretofore provided to prevent undue outward movement of the outer spindle to an unsafe or unstable position, in case the operator should attempt to lift the load beyond the intended range of 25 the jack usually consisted of a nut threaded upon the inner end of the spindle. In accordance with this part of my invention, spring means are provided for limiting the outward movement of one spindle, said 30 means preferably comprising a spring ring arranged at the lower end of the outer spindle so as to prevent an undue binding action between the outer spindle and the housing when starting to lower the jack 35 from its fully extended position.

Irrespective of the foregoing features, but 40 preferably in combination therewith, the invention also comprehends a structure in which a nut is detachably fastened on top of the housing, the outer spindle having an external thread throughout substantially its entire length, and also having an internal thread near the top only for engagement 45 with an inner spindle which is externally threaded for substantially its entire length. In this way the total length of screw threads is reduced to a minimum, and the housing 50 may have its compression part of smooth-bore cast iron and its screw-threaded part of a separate piece better adapted for the purpose.

Heretofore no means have been provided to compel the total longitudinal movement of one spindle before another spindle starts 55 to move relatively thereto, with the result

that the comparatively great specific friction at the threads of an inner spindle, due to its reduced diameter relatively to that of an outer spindle, sometimes causes the two or more spindles to rise simultaneously or 60 alternately, thus producing an uneven and therefore a jerky movement by the operator. In accordance with this part of my invention, and irrespective of the other features enumerated herein, all but one of the spindles 65 are prevented from rising at a time by resilient means or by a clutch, which is overcome or disengaged when the rising spindle reaches a predetermined point of its relative longitudinal movement, whereupon another 70 of the spindles is then released for longitudinal movement to further extend the jack. In the case of a jack having two spindles, as specifically described hereinafter, the spring-pressed plunger or disengageable 75 clutch may be arranged between the housing and the outer spindle, and may be released when the inner spindle reaches its outer limit of travel in the outer spindle and re-engaged when the outer spindle reaches its 80 collapsed position. Preferably such a spring-pressed plunger is carried by the housing and is arranged to enter a hole in the outer spindle when that spindle is collapsed, and to be disengaged from the outer 85 spindle when that spindle is turned after the inner spindle reaches its outer limit of travel. For instance, as specifically described hereinafter, the nut fastened to the housing may contain the plunger and a collar or flange at the top of the outer spindle 90 may have the hole to resiliently lock it until the inner spindle, at its upper limit of travel, exerts a disengaging turning force on the outer spindle. In this way the beginning of the lift of the outer spindle is made subservient to or dependent upon the position of the inner spindle.

In the accompanying drawings illustrating the preferred form of my invention in 100 application, as an example, to a jack having two spindles and particularly adapted for trucks,

Fig. 1 is a sectional elevation of the jack collapsed; Fig. 2 is a similar view of the 105 jack fully extended; Fig. 3 is a view on line 3—3 of Fig. 1; and Figs. 4 and 5 are enlarged sections on lines 4—4 and 5—5, respectively, of Fig. 1.

The smooth-bore cast iron housing 1 car- 110

ries a stamped steel cover plate 2 fastened to its bottom by the bolts 3, and a steel or bronze nut 4 fastened in its top by the screws 5. Screw threaded into the nut 4 is an outer spindle 6 of cast iron having an upper flange or collar 7 perforated at 8. In the fully collapsed position of the outer spindle 6, as shown in Figs. 1 and 4, the spring-pressed plunger 9, retained in the nut 4, snaps into the hole 8 to resiliently lock the outer spindle against turning in the nut.

The spring ring 10 embraces the lower end of the outer spindle 6 and has one of its ends bent over and projecting into the hole 11 (Fig. 5) to prevent the outer spindle from screwing beyond full engagement with the nut 4, when it is pressed against the lower surface of the nut in the fully raised position of the outer spindle (Fig. 2).

20 The outer spindle 6 is externally screw-threaded throughout substantially its entire length for engagement with the nut 4, and has an internally screw-threaded upper portion 12.

25 The solid steel inner spindle 13, which is screw-threaded throughout most of its length for engagement with the internal threads of the outer spindle, has an enlarged lower portion 14 arranged to frictionally engage the lower surface of the portion 12 of the outer spindle; and a neck 15 carrying at its outer end a relatively rotatable load-engaging block 16 having a ball 17 spring-pressed into the peripheral groove 18.

30 Mounted fast on the neck 15, just below the load-engaging block 16, is a ratchet pinion 19 which is engaged by one or the other arms of a reversible yoke pawl 20 pivoted on the stud 21. An operating handle comprises 40 a frame 22 loosely journaled on the neck 15 and carrying besides the stud 21 a spring-pressed plunger 23 which holds the pawl 20 in a set position. The handle also carries a downwardly offset socket 24 for receiving a bar 25 with a spring-pressed ball 26 adapted to enter a groove 27 to resiliently retain the bar in the socket.

To extend the jack from the fully collapsed position shown in Fig. 1, the reversible pawl 20 is set to turn the pinion 19 and the inner spindle 13 in the direction indicated by the arrows in Figs. 1 and 3, the bar 25 being oscillated by the operator. The plunger 9 then resiliently holds the outer spindle 6 against turning. Whether or not the block 16 engages the load, the inner spindle 13 continues to rise to its outermost position relatively to the inner spindle, at which time the enlarged portion 14 frictionally engages the under surface of the enlarged upper portion 12 of the outer spindle. This gripping action is sufficient to disengage the collar 7 from the plunger 9, forcing the plunger out of the hole 8 as the collar begins 65 to turn. The outer spindle 6 then rises in

the housing, lifting the inner spindle 13 with it, until the spring ring 10 comes into contact with the under surface of the nut 4, the jack then being in its fully extended position as shown in Fig. 2. It is obvious 70 from the foregoing that the load may be lifted from the foregoing that the load may be lifted from the fully collapsed position of the jack to the fully extended position thereof, or to any intermediate point of that extension.

To collapse the jack from its fully extended or any intermediate position, the pawl 20 is reversed so as to turn the pinion 19 in the direction indicated by the arrow in Fig. 2. As a result of the binding action 80 then existing between the lower portion 14 and the under surface of the enlarged portion 12, the outer spindle is screwed down in the housing until the plunger 9 snaps into the hole 8. The binding friction between the spindles is then overcome by a slight additional turning effort, whereupon the same direction of operation of the rod 25 lowers the inner spindle 13 in the outer spindle 6 until the jack is fully collapsed as 90 shown in Fig. 1.

What I claim is:

1. In a jack, a housing, an outer spindle longitudinally movable in said housing, an inner spindle in screw-threaded engagement with said outer spindle, means for limiting the outward movement of said inner spindle in said outer spindle, means for limiting the outward movement of said outer spindle in said housing, one of said means 95 embodying a spring, and means for rotating said inner spindle.

2. In a jack, a housing, an outer spindle longitudinally movable in said housing, a spring ring fastened to the lower end of 105 said outer spindle for limiting the outward movement of said outer spindle in said housing, an inner spindle in screw-threaded engagement with said outer spindle, means for limiting the outward movement of said inner spindle in said outer spindle, and means for rotating said inner spindle.

3. In a jack, a smooth-bore housing, a nut detachably fastened on top of said housing, an outer spindle having an upper portion with an internal thread and also having an external thread throughout substantially its entire length for engagement with said nut, an inner spindle externally threaded 115 throughout substantially its entire length for engagement with the internal thread of said upper portion, and means for rotating the inner spindle.

4. In a jack, a housing, an outer spindle adapted for longitudinal movements in said housing, an inner spindle adapted for longitudinal movements in the outer spindle, a disengageable clutch constructed and arranged to hold one spindle against longi- 125 130

tudinal movement until the other spindle has reached substantially its outer limit of longitudinal movement to become disengaged upon further movement of said other 5 spindle, and means for rotating the inner spindle.

5. In a jack, a housing, an outer spindle adapted for longitudinal movements in said housing, a load-engaging spindle adapted 10 for longitudinal movements in the outer spindle, resilient means constructed and arranged to hold one spindle against longitudinal movement until the other spindle has reached substantially its outer limit of 15 longitudinal movement, and means for rotating the inner spindle.

6. In a jack, a housing, an outer spindle adapted for longitudinal movements in said housing, an inner spindle adapted for longitudinal movements in the outer spindle, said outer spindle and housing forming two members one of which has a hole and the other of which carries a spring-pressed plunger adapted to engage said hole in one 25 of the extreme longitudinal positions of the outer spindle, and means for rotating the inner spindle.

7. In a jack, a housing, an outer spindle adapted for longitudinal movements in said 30 housing, an inner spindle adapted for longitudinal movements in the outer spindle, a disengageable clutch between the housing and the outer spindle to hold the outer spindle against the longitudinal movement 35 in the housing until the inner spindle has reached substantially its outer limit of longitudinal movement in the outer spindle, to become disengaged upon further movement of said inner spindle and means for 40 rotating the inner spindle.

8. In a jack, a housing, an outer spindle

having a hole and being adapted for longitudinal movements in said housing, an inner spindle adapted for longitudinal movements in the outer spindle, a spring-pressed 45 plunger carried by the housing and adapted to extend into said hole to resiliently hold the outer spindle against longitudinal movement in the housing, and means for rotating the inner spindle. 50

9. In a jack, a housing, a nut fastened on top of said housing, a spring-pressed plunger located in said nut, an outer spindle adapted for longitudinal movements in said housing and having an upper collar with a hole 55 arranged to be engaged by the plunger when the outer spindle is collapsed, an inner spindle adapted for longitudinal movements in the outer spindle, and means for rotating the inner spindle. 60

10. In a jack; a smooth-bore housing; a nut fastened on top of said housing; a spring-pressed plunger carried by said nut; an outer spindle externally threaded throughout substantially its entire length 65 for engagement with said nut and having an upper portion with a flange and an internal thread, said flange having a hole adapted to be engaged by said plunger in the collapsed position of the outer spindle, an inner spindle externally threaded throughout substantially its entire length for engagement with the internal threads of the upper portion of said outer spindle, 70 said outer spindle having means limiting its upper movements in said housing and the inner spindle having means limiting its outer movements in the outer spindle; and means for rotating the inner spindle. 75

In testimony whereof I affix my signature. 80

GEORGE F. KUEHN.
